SHUTTER AWNING

J. Otto Ackerman, Cleveland, Ohio

Application September 28, 1940, Serial No. 358,869

8 Claims. (Cl. 156—17)

The invention relates to awnings having a plurality of overlapping shutters or vanes which may be opened to admit light and air, or closed to exclude direct sunlight and shed rain.

For convenience, all of the vanes of a shutter awning should be arranged to be opened or closed simultaneously by a single operating bar, so that the awning can be opened and closed manually by one person. With prior operating mechanisms for shutter awnings difficulty has been experienced in making the opening operation easy enough to be satisfactorily accomplished by one person, particularly if the vanes are elongated as where the awning is positioned over a show window or store front.

This difficulty is due largely to the fact that in opening the vanes they must be raised or lifted to swing upward from their closed overlapping position, and the weight of the vanes requires a heavy pull on the operating bar, especially where elongated vanes are used.

Moreover, in prior operating mechanisms for shutter awnings the tendency has been to provide a relatively complicated system of levers and linkages in attempting to produce ease of operation, with the result that the operating mechanism has been increasingly expensive and in some cases has required frequent lubrication.

Another disadvantage with certain prior operating mechanisms for shutter awnings, in which vane supporting arms are pivoted intermediate their ends beyond the vanes on a frame member and have their free ends pivoted to a parallel operating bar, is that the top vane cannot swing under the stationary weatherstrip at the top of the awning without notching the top vane, and this permits moisture to leak through the notches when the awning is closed.

It is therefore a principal object of the present invention to provide a shutter awning having an improved operating mechanism making the opening operation extremely easy so as to permit the manual operation of longer and heavier shutter awnings by one person.

Another object is to provide an extremely simple and inexpensive operating mechanism for a shutter awning.

A further object is to provide an improved shutter awning operating mechanism in which the pivots mounting the vanes for swinging are so positioned that the vanes are substantially balanced.

Another object is to provide an improved shutter awning operating mechanism which requires only one operating bar and permits location of

the bar at any place along the length of the vanes.

And finally, it is an object of the present invention to provide an improved shutter awning which has all the advantages and overcomes the disadvantages of prior shutter awning constructions.

These and other objects are accomplished by the improvements comprising the present invention, preferred embodiments of which are shown by way of example in the accompanying drawings, and which is hereinafter described and claimed.

In general terms the invention may be stated as including laterally spaced frame members extending angularly downward from a support, means pivoting the vanes on said frame members at points located substantially centrally of the width of the vanes, and an operating bar parallel with said frame members and pivotally connected to said vanes for opening and closing the same.

Referring to the drawings forming part hereof,

Figure 1 is a vertical sectional view showing one embodiment of the improved shutter awning applied to a window, as on line 1—1, Fig. 4, the awning vanes being shown in closed position;

Fig. 2 is a fragmentary view similar to Fig. 1, showing the shutter awning detached and the vanes in fully opened position.

Fig. 3 is a fragmentary broken rear sectional view as on line 3—3, Fig. 1;

Fig. 4 is a fragmentary elevation on a reduced scale looking toward the rear side of the shutter awning shown in Fig. 1 with the vanes in partially open position;

Fig. 5 is a fragmentary vertical sectional view of another embodiment of the improved shutter awning as on line 5—5, Fig. 8, with the vanes in closed position;

Fig. 6 is a similar view with the vanes in fully opened position;

Fig. 7 is a fragmentary rear sectional view as on line 7—7, Fig. 5; and

Fig. 8 is a fragmentary elevation partly in section on a reduced scale looking toward the rear side of the shutter awning shown in Figs. 5 and 6, with the vanes in partially open position.

Similar numerals refer to similar parts throughout the drawings.

Referring first to the embodiment of the invention shown in Figs. 1 to 4 inclusive, in Fig. 1 the invention is shown applied to a conventional double sash window having the upper sash 9 and

the lower sash 10 vertically slidable in the window frame indicated generally at 11.

The improved shutter awning is indicated generally at 12 and includes rafter angles 13 secured at their upper ends to a laterally extending supporting angle 14 which is secured to the window frame 11 in a usual fashion. Preferably a stationary weatherstrip 15 is supported on the angle 14 and extends outwardly for overlapping the uppermost vane of the shutter awning.

The number of rafter angles 13 may vary according to the lateral extent of the awning, two such rafter angles being used one at each side of an ordinary window, and where the awning is elongated a number of rafter angles may be spaced at suitable intervals.

The rafter angles 13 depend angularly downward and outward from the supporting angle 14 and are rigidly secured at their lower ends to the sides of the window by struts or braces 16 which may be twisted metal strips as shown. In the embodiment of the invention shown in Figs. 1 to 4 inclusive, the bottom end portions of the rafter angles 13 are bent angularly outward as shown at 17 and have a laterally extending angle 18 secured to their outer ends, a bottom awning strip or valance 19 being secured to said angle 18. As shown, the braces 16 maybe bent upwardly at their outer ends around and over the angle 18 to connect the bottom end of the awning frame to the window frame.

The vanes or shutters are indicated at 20 and are mounted on the rafter angles in overlapping relation in closed position as shown in Fig. 1. Each vane 20 has secured on its under side above each rafter angle a bracket 21, one flange 22 of which is secured to the vane and the other flange 23 projects rearwardly from the vane at right angles thereto.

At intervals longitudinally of the rafter angle outwardly projecting arms 24 are rigidly secured thereto, and these arms 24 are pivotally connected at their outer ends to the rearwardly projecting flanges of the brackets 21. The pivots 25 connecting the brackets 21 to the arms 24 are located substantially centrally of the widths of the vanes, that is, each pivot 25 is located substantially midway between the upper and lower edge of the vane 20 carried thereby, as viewed in Figs. 1 and 3.

As shown in Fig. 2 the pivot points 25 are spaced outwardly from the angles 13 a sufficient distance to permit the vanes 20 to swing through substantially 90° to fully open position without interfering with the rafter angles, and because of the relative location of the pivot points 25 the weatherstrip 15 can be made to overlap the uppermost vane 20 in both open and closed position without interfering with its swinging movement and without requiring notching of the uppermost vane.

The means for opening and closing the vanes 20 is preferably a single operating bar 26 which is disposed parallel with the rafter angles, and which is pivotally connected to all of the vanes 20 by means of links 27 pivoted at one end to the operating bar 26 and having an angular flange 27' at their other ends secured directly to the under sides of the vanes 20. Since the links 27 are connected to the vanes independently of the brackets 21, the operating bar can be located anywhere along the lateral extent of the awning, and as shown in Fig. 4, the operating bar 26 is located substantially midway between two spaced rafter angles.

Means for moving the operating bar manually may include a rearwardly projecting arm 28 secured to the operating bar 26 and having a cable 29 connected to its rear end, whereby a downward pull on the cable 29 will move the operating bar 26 downwardly and swing the vanes 20 about their respective pivots 25 to the position shown in Fig. 2.

Since the pivots 25 are located substantially centrally of the vanes 20, that is, substantially midway between their top and bottom edges, the vanes have a substantially balanced pivotal mounting, so that when the operating bar is moved downwardly to raise the vanes there is very little effective weight to be lifted by the pull on the operating bar.

Consequently very little effort is required to open the awning, with the result that vanes of increased length can be opened easily by a single person. Likewise, if it is desired to ornament the outer surface of the vanes as by shingling or the like, the same can be done even though considerable weight is added, without greatly increasing the operating effort required because of the balanced mounting of the vanes.

In the embodiment of the invention shown in Figs. 5 to 8 inclusive, the rafter angles 13a are secured at their upper ends to a laterally extending supporting angle 14a which is secured to the window frame, and the stationary weatherstrip 15a is supported on the angle 14a and extends outwardly therefrom for overlapping the uppermost vane of the shutter awning.

The rafter angles 13a are provided with ears 30a projecting outwardly therefrom at spaced intervals longitudinally of the rafter angles. Preferably the ears 30a formed integral with the rafter angles 13a, and the ears are adapted to pivotally mount the vanes 20a in overlapping relation in closed position as shown in Fig. 5.

Each vane 20a has secured on its underside a bracket 21a, one flange 22a of which is secured to the vane and the other flange 23a projects rearwardly from the vane at right angles thereto. The ears 30a are pivotally connected at their outer ends to the flanges 23a of the brackets 21a, and the pivots 25a connecting the ears to the brackets are located substantially centrally of the widths of the vanes, that is, substantially midway between the upper and lower edges of the vanes, as viewed in Figs. 5 and 7.

As shown in Fig. 6, the outer ends of the ears 30a are spaced a substantial distance outwardly from the rafter angles 13a and notches 31a are provided between the ears so that the vanes 20a can swing through substantially 90° to fully open position without interfering with the rafter angles. Moreover, because of the location of the pivots 25a with respect to the vanes 20a, the weatherstrip 15a can be made to overlap the uppermost vane without interfering with its swinging movement and without requiring notching of the uppermost vane.

The means for opening and closing the vanes 20a is preferably a single operating bar 26a which is disposed parallel with the rafter angles and is pivotally connected to arms 32a projecting rearwardly from each of the brackets 21a. Thus the operating bar 26a is located closely adjacent to one of the rafter angles 13a as best shown in Fig. 8, and does not require separate arms for pivotally connecting the operating bar to the vanes 20a.

Means for moving the operating bar manually may include a rearwardly projecting arm

28a secured to the operating bar 26a and having a cable 29a connected to its rear end, whereby a downward pull on the cable 29a will move the operating bar downwardly and swing the vanes 20a about their respective pivots 25a to the open position shown in Fig. 6.

The pivots 25a are located substantially centrally of the vanes 20a so as to provide a substantially balanced pivotal mounting for the vanes and obtain the same advantages resulting from ease of operation as are obtained with the embodiment of the invention shown in Figs. 1 to 4 inclusive.

The improved operating mechanism in both embodiments of the invention is extremely simple and inexpensive and overcomes the disadvantages of prior shutter awning constructions, at the same time accomplishing all of the advantages of those constructions.

I claim:

1. Shutter awning construction including laterally spaced rafter angles secured at their upper ends to a support and depending angularly downward and outward therefrom, said rafter angles having spaced projections at intervals longitudinally thereof, vanes pivotally mounted substantially centrally of their widths on said projections in overlapping relation with each other and adapted for swinging through substantially 90° to fully open position, and an operating bar pivotally connected with all of said vanes.

2. Shutter awning construction including laterally spaced rafter angles secured at their upper ends to a support and depending angularly downward and outward therefrom, said rafter angles having spaced projections at intervals longitudinally thereof, vanes pivotally mounted substantially centrally of their widths on said projections in overlapping relation with each other and adapted for swinging through substantially 90° to fully open position, a weatherstrip secured to said support overlapping the uppermost vane in its open and closed positions, and an operating bar pivotally connected with all of said vanes.

3. Shutter awning construction including laterally spaced rafter angles secured at their upper ends to a support and depending angularly downward and outward therefrom, said rafter angles having spaced projections at intervals longitudinally thereof, vanes pivotally mounted on said projections at positions providing a substantially balanced mounting for the vanes, and an operating bar pivotally connected with all of said vanes.

4. Shutter awning construction including laterally spaced rafter angles secured at their upper ends to a support and depending angularly downward and outward therefrom, said rafter

angles having spaced projections at intervals longitudinally thereof, vanes pivotally mounted on said projections at positions providing a substantially balanced mounting for the vanes, a weatherstrip secured to said support overlapping the uppermost vane at its open and closed positions, and an operating bar pivotally connected with all of said vanes.

5. Shutter awning construction including laterally spaced rafter angles secured at their upper ends to a support and depending angularly downward and outward therefrom, arms secured at intervals to the rafter angles and projecting outwardly therefrom, vanes pivotally mounted substantially centrally of their widths on said arms, an operating bar positioned in parallel relation with said rafter angles, and links pivotally connecting said operating bar with said vanes.

6. Shutter awning construction including laterally spaced rafter angles secured at their upper ends to a support and depending angularly downward and outward therefrom, arms secured to said rafter angles at intervals longitudinally thereof and projecting outwardly therefrom, a plurality of overlapping vanes, brackets pivotally mounting said vanes on said arms at points located substantially centrally of the vane widths, an operating bar disposed in parallel relation with said rafter angles, and links pivotally connecting the operating bar with the vanes independently of the brackets.

7. Shutter awning construction including laterally spaced rafter angles secured at their upper ends to a support and depending angularly downward and outward therefrom, said rafter angles having spaced ears projecting outwardly therefrom at intervals longitudinally thereof, vanes having brackets pivotally mounted substantially centrally of the widths of the vanes on said ears in overlapping relation with each other and adapted for swinging through substantially 90° to fully open position, and an operating bar pivotally connected with the ends of said brackets for opening and closing said vanes.

8. Shutter awning construction including laterally spaced rafter angles secured at their upper ends to a support and depending angularly downward and outward therefrom, said rafter angles having spaced integral ears projecting outwardly therefrom at intervals longitudinally thereof, a plurality of overlapping vanes, brackets secured to the vanes and pivoted on said ears at points located centrally of the width of said vanes, said vanes being adapted to swing about said pivot points between adjacent ears to fully open position, and an operating bar having a pivotal connection with one end of each bracket.

J. OTTO ACKERMAN.
